DOOR SECURING DEVICE

Allen Chambers, Independence, and Roy E. Gearhart, Kansas City, Mo., assignors of one-third to W. E. Ludwig, Kansas City, Mo.

Application April 20, 1942, Serial No. 439,790

4 Claims. (Cl. 70—93)

This invention relates to improvements in a door securing device and has particular reference to a door securing device wherein the door is secured to the door jamb for a limited opening position.

In devices of this character and especially where the door securing device is operable from both inside and outside the door, much difficulty has been experienced in properly positioning the parts and adjusting them to doors of different thicknesses.

This invention is an improvement over our pending application Serial No. 419,956, and has for its principal object the provision of a door securing device wherein the parts are easily assembled and can be positioned on the door structure by any carpenter without the possibility of having the operating parts out of proper alignment.

Another object of the present invention is the provision of a door securing device including a slidably mounted bolt having three selective operating positions each of which is mechanically indicated to the operator.

A further object is the provision of a door securing device which is provided with a bolt correctly assembled which is reversible to accommodate doors opening in the opposite directions.

Other objects are simplicity and economy of construction, ease and efficiency of operation, and adaptability for use with the various types of doors, and to affect different combinations of opening and closing from opposite sides of the door.

With these objects as well as others which will appear during the course of the specification, in view, reference will now be had to the drawings wherein.

Figure 1 is an inside elevation of a portion of a door operatively mounted in the door frame and having a securing device embodying this invention.

Fig. 2 is a cross sectional view taken on line II—II of Fig. 1 with the door shown in the partially open position in dotted lines.

Fig. 3 is an outside elevation of a portion of the door and its mounting frame showing certain portions of the door securing device.

Fig. 4 is an enlarged view of a portion of the face of the door jamb with the extension bar and housing shown in position thereon and with parts broken away to show the extension bar in the closed position in solid lines, and extended in dotted lines.

Fig. 5 is an enlarged sectional view taken on

line V—V of Fig. 1 with the door shown in the partially open position and the bar extended.

Fig. 6 is a sectional view taken on line VI—VI of Fig. 4 with a portion of the door showing.

Fig. 7 is a foreshortened sectional view taken on line VII—VII of Fig. 8 with certain of the parts left in elevation and the bolt shown in the retracted position in dotted lines.

Fig. 8 is an enlarged sectional view taken on line VIII—VIII of Fig. 3.

Fig. 9 is a vertical sectional view taken on line IX—IX of Fig. 7.

Fig. 10 is a vertical sectional view taken on line X—X of Fig. 7.

Fig. 11 is an enlarged detailed elevational view of the bolt operating lever and certain of its associated parts shown in its two extreme positions.

Fig. 12 is an enlarged fragmentary sectional view of certain of the lever operating parts.

Fig. 13 is a detached face view of the door jamb housing.

Fig. 14 is a vertical sectional view taken on line XIV—XIV of Fig. 7.

Fig. 15 is an elevational view of the lock bolt.

Fig. 16 is a perspective view of the extension sleeve.

Fig. 17 is a sectional view similar to Fig. 8 with certain modifications of some of the parts.

Fig. 18 is a fragmentary sectional view taken on line XVIII—XVIII of Fig. 17.

Fig. 19 is a fragmentary enlarged sectional view taken on line XIX—XIX of Fig. 18.

Fig. 20 is a perspective view of the lever securing sleeve.

Fig. 21 is a vertical view partially in section with certain modifications of some of the parts.

Fig. 22 is a horizontal sectional view taken on line XXII—XXII of Fig. 21.

Fig. 23 is a fragmentary reduced elevational view of the face view of the door jamb with the associated parts partially broken away.

Throughout the several views, like reference characters designate similar parts, and the numeral 20 is a door frame in which is mounted a door 22 for swinging movement on hinges 24. The door frame is secured to studs 26 and includes a door jamb 28 having its face 30 slightly spaced apart from the edge of the door when the door is in the closed position.

A door stop 32 secured to the face of jamb 28 serves as an abutment for the door whereby it is maintained in substantially flush relation with the inner edge of jamb 28 when the door is closed.

The usual door casings 34 partially overlap the

edge of jamb 28 and extend outwardly therefrom.

For securely holding the door in the partially open position for ventilation and for protection from intrusion when answering the door, the following door securing device is provided. The preferred form of this device is shown in Figs. 1-16 inclusive, and includes a housing 36, having side walls 38 and 40 spaced apart with the inside wall 38 offset and welded at certain points W to the planar outside wall 40. The housing is open at its front edge 48. Side wall 40 which is normally adjacent the edge of door 22 is provided adjacent its upper end with a bight 42.

It will be noted that the width of housing 36 is substantially the thickness of the door 22 and it is morticed into jamb 28 so that the outer surface of wall 40 is in planar relation with the face 30 of the door jamb. The housing 36 is held in position by means of a counter-sunk screw 44 which is disposed flush with the outer surface of wall 38 and in alignment with opening 45 formed through wall 40 as clearly shown in Fig. 6. An offset portion 47 formed inwardly in wall 38, is directly opposite bight 42 formed in the outer housing wall 40 and extends transversely across the wall 38 to the front edge of the housing and has a forwardly projecting tongue 49 to overlap the casing 34 which may be slightly beveled or offset at 48.

The screw 44 is so positioned, relative to the hole 45 formed in the side wall 40, that it is not accessible therethrough when the extension bar 50, pivoted at 66 within said housing, is in the normal positions as shown in Fig. 4; however, when the extension bar is moved to the extended and completely raised position with the door wide open, the bar is moved from between hole 45 and the head of the screw so that the screw can be removed or set. A suitable screw 52 may be provided for securing the end portion of the housing against displacement.

It will be noted that the door jamb is recessed at 54 to receive the lateral flanges 56 formed in the wall 38 in horizontal alignment with the bight 42 formed in wall 40. These flanges 56 are vertically elongated to compensate for sagging of the door and are snugly fitted into recess 54 to hold the housing 36 in position and against transverse movement when the limiting bar is in use.

Extension bar 50 is provided with a longitudinal slot 58 having an enlarged portion 60 at its upper end and outwardly disposed offset 62 at its lower end. The bar is downwardly tapered and rests against offset 64 of wall 38 when its outer edge is flush with the outer face of housing 36. The pivotal pin 66 of the extension bar 50 is slightly above bight 42 so that the pin 66 is definitely secured in both of the walls 38 and 40 as clearly shown in Fig. 6.

A tension spring 68 rigidly secured to wall 38 at 70 extends upwardly to engage extension bar 50 above pivot 66 thereby tending to urge the bar against offset 64 when the bar is in the normal position and also serves to urge the outer extremity of the bar 50 downwardly when the bar is in the extended position shown in dotted lines in Fig. 4. Other types of spring tension might be utilized for this same purpose without any material changes in the general structure of the device.

One form of suitable adjustable means carried by the door for operatively engaging the extension bar 50 is shown in the form of a bolt 72 slidably mounted in a housing 74 which is inserted in a recess 76 formed inwardly from the edge sur-

face of the door. This housing is securely anchored by means of screws 78 which pass through housing plate 80. Bolt 72 is provided at its inner portion with a bifurcated member 82 which is disposed in a vertical position with its legs 81 and 83 resting against the respective flanges 85 to guide the bolt during its sliding movement. Leg 81 is provided with a notch 84 and leg 83 has an outturned tongue 86 to which is attached one end 10 of a coil spring 87 while the other end thereof is attached to the outer portion of housing 74 at 71. This spring 87 serves to constantly urge the bolt 72 to the extended position with the forward end of the bifurcated member 82 resting against the shoulder 88 of housing 74 as shown in solid lines in Fig. 7.

The means for operating bolt 72 is best shown in Figs. 7, 8, 10, 11, and 12, wherein the bolt is operated from inside the room by hand knob 94 and from outside the room by key 96. Knob 94 has an axial bore 98 into which is slidably mounted a sleeve 100 having a laterally disposed pin 102 which engages groove 104 in the shank of knob 94 to prevent relative rotation of the knob and sleeve. Referring to Fig. 12, it will be noted that the shank 106 of knob 94 is offset at 108 to pass through an opening 109 formed through the escutcheon plate 110, and is further offset at 112 to receive the washer 114. The outer end of shank 106 is upset to secure the washer 114 tightly in position and when so mounted, the knob can be rotated in the escutcheon plate 110. The sleeve 100 extends through a plate 118 positioned between the escutcheon 110, the door 22, thence through an opening 120 formed in the door to meet the housing 74. Housing 74 is perforated at 121 in axial alignment with the sleeve 100, which extends therethrough to receive the lever 122 as clearly shown in Figs. 8 and 12. The outer extremity of sleeve 100 is slotted at 124 to receive the diametrically opposed radial lugs 126 which extend inwardly from the walls of circular opening 128 in the hub 130 of lever 122. Lugs 126, with their supporting ring 127, are offset relative to hub 130 so that ring 127 snugly fits into opening 121 in housing 74. A keeper plate 132, perforated at 134, is adapted to receive the outer end portion of sleeve 100 and to rest against the hub 130, with its inturned legs secured to the housing 74 (see Fig. 8). Sleeve 100 has a transverse partition 138 against which one end of compression spring 140 rests, while its other end rests against the inner bottom of bore 98. This spring is always under compression and permits the adjustment of the total length of the knob and sleeve to accommodate doors of different thicknesses.

The outer end portion of lever 122 has an outturned tongue 142 which is adapted to fit into notch 84 formed in lever leg 81 so that as the knob 94 is rotated the lever will be oscillated to cause a movement of the bolt to or from the extended position. The escutcheon 110 is secured to the door by means of screws 144 thus insuring the knob and its associated parts against longitudinal movement relative to the door.

An opening 146 extending from the outside of the door to recess 76 is so positioned that the barrel 148 of lock 150 will be positioned in axial alignment with the sleeve 100. This lock is one of the well-known tumbler type which is normally locked and can be operated by means of key 96 to rotate the operating bar 152 which is adapted to extend into sleeve 100 to engage radial lugs 126 whereby the lever 122 may be operated

as the key 96 is turned in the lock. This operating bar is scored or grooved at 154 so that it may be easily shortened to accommodate thin doors by simply breaking off any desired number of sections of the bar determined by said grooves. The lock is secured against removal by means of screws 156 which pass through plate 118 into the door to engage lugs 158 which are integral with the lock 150. Referring to Fig. 7, it will be noted that the screws 156 are positioned slightly above the horizontal diameter of sleeve 100 and that two sets of openings 157 are formed through wall of housing 74 and also two sets of openings 159 are formed through plate 118 (see Fig. 14) so that the housing 74 may be turned over when mounting the door to operate in the reverse direction. When so reversed, the screws 156 will pass through the other set of openings. This double set of openings in the plate 118 makes it possible to reverse the door latching mechanism without inverting the lock.

A spring member 160 secured at 162 to housing 74 is provided with an offset portion 164 which is in the path of travel of the bifurcated member 82. This spring is so positioned that the edge 165 of bifurcated member 82 will contact the offset portion 164 when the bolt is in its intermediate position to engage the extension bar 50. It will be noted that the bolt 72 is chamfered at 167 so as to serve as a latch bolt. The outer end portion of bolt 72 is provided with top and bottom parallel grooves 168 thus forming a guide-way to receive the edges of bar 50 adjacent slot 58 when the door is to be opened to a limited distance. It will be observed that the enlarged portion 60 of slot 58 gradually narrows to meet the uniform slot 58 thus making it possible to permit the bolt to properly turn therein when the door is moved toward the open position. After the bolt has engaged in slot 58 it can not be moved transversely therefrom without distorting the metal parts.

For the purpose of retaining the bolt in the retracted position when a latch bolt hereinafter described is utilized, the following means is provided. A sleeve 169 is positioned in door 22 with its inner end projecting through the wall of housing 74. This sleeve is provided with a flange 170 which is adapted to receive screws 172 whereby the sleeve is held in position. A bolt 174 having an operating knob 176 is provided with a helical groove 178 to receive a stationary pin 180 carried by sleeve 169. It will be noted that normally the bolt 174 does not contact the door bolt 72, however, when the door bolt is retracted, a notch 182 formed therein will be in register with bolt 174 so that by simply rotating knob 176 in the proper direction, the bolt 174 will be forced into notch 182 thus retaining the bolt in the retracted position against the action of spring 87.

Reference will now be had to the auxiliary door latching mechanism 182 which is positioned above the door locking mechanism and is definitely positioned relative thereto by means of housing plate 80 to which it is secured. The door is morticed inwardly from its edge at 184 to receive a housing 186 in which is slidably mounted a latch bolt 188 having a shank 190. A guide pin 192 mounted in housing 186 passes through slot 194 formed through shank 190 to limit the inward and outward movement of the latch bolt and to maintain it in proper alignment. A compression spring 196 is mounted on shank 190 with one of its ends resting against

the head of the bolt 188 and its other end resting against stops 198 which are integral with the housing 186. It will be noted that the latch bolt, due to the action of spring 196, is normally in the extended position so that it will enter the opening 199 in plates 38 and 40 and may be retracted by means of knobs 200 and 202 which are positioned respectively on the inside and outside of the door and are joined together by means of square rod 204. This rod 204 is mounted in a square hole 206 formed through the hub 208 of lever 210. This lever is slotted at 212 to receive the pin 214 which is rigidly mounted in the inner end portion of shank 190. By simply turning either knob 200 or 202 the latch bolt will be retracted and the door can be opened from either side. A projection 191 of plate 38 extending over the casting 34 serves as a strike plate for latch 188.

20 The modified form shown in Figs. 17, 18, 19, and 20 is provided with a bolt 216 having a square end which precludes automatic retraction thereof by simply closing the door against the strike plate, thus requiring the use of the key 96 to retract the bolt when it is desired to lock the door when leaving the room.

Another feature is the novel means provided for securing the lever arm 218 to the sleeve 100. The housing wall 74 is inwardly offset at 220 and 30 perforated at 222 to receive the reduced body portion 224 of sleeve 226. The head 228 of sleeve 226 is positioned between the housing plate 74 and the door structure 22 to extend through opening 222 for free rotary movement. The outer extremity of the sleeve 226 is reduced at 230 to receive the hub 232 of lever 218 so that the inturned radial lugs 234, integral with hub 232, will enter the diametrically disposed slots 236 formed in sleeve 226 and will also pass through 35 slots 124 formed in sleeve 100. The outer end of sleeve 226 is then peened over sufficiently to secure the hub 232 against movement relative to sleeve 226. The lock 150 on the outside of the door is fitted through an escutcheon 238 which 40 is secured in position by means of screws 240. This type of connection between the operating knob 94 and the operating lever 218 is very efficient and can be made at a very small cost. The general construction of the door securing 45 device is similar to that shown in the preferred form as indicated by the identifying characters.

The operation of the door securing device shown in the preferred form is as follows. When the parts are in the position shown in Fig. 8 55 wherein the door is shown closed, the spring 87 urges bolt 72 to the entirely extended position so that the outer end portion of the bolt 72 engages against flange 56 to prevent accidental outward movement of the door from its casing. When bolt 72 is in the extended position, it will be noted that the grooves 168 formed adjacent the outer end thereof will be extended beyond the extension bar 50. When it is desired to open the door from the inside, the operator simply grasps 60 knob 94 and turns it to move bolt 72 against the action of spring 87 to the retracted position shown in dotted lines in Fig. 7. The door can now be opened and when the operator releases the knob 94, bolt 72 will be automatically extended and in position to act as a latch bolt when the door is swung to the closed position. This same operation can be performed from outside the room by inserting the key 96 into lock 70 150, then turning the key to cause a movement of bolt 72 as described above.

When it is desired to engage the extension bar 50 by means of bolt 72, the operator turns knob 94 until shoulder 166 of the bolt contacts offset 164 of spring 160. This spring is sufficiently strong to indicate to the operator the position of the bolt. When the bolt is in this partially extended position, the grooves 168 in bolt 72 will be in alignment with bar 50 and the outer end of the bolt will be clear of flange 56. The door can now be moved toward the open position shown in Fig. 5 with the bolt in engagement with the slot 58 of bar 50 from which it can not be removed without distorting the metal parts.

By referring to Fig. 4 it will be noted that the bolt 72 will be positioned behind shoulder 62 when the door is partially opened so that the door will be held in a fixed position against opening and closing until the bar 50 is slightly raised to enter the reduced portion of slot 58. The slot 58 is sufficiently wide to permit the proper travel of the narrow necked portion of bolt 72 therethrough. Any desired distance of door opening can be obtained by varying the length of bar 50.

When the dead bolt 216 is used as shown in Figs. 17, 18, 19, and 20 it will be noted that the door can not be closed from the outside without using key 96, since there is no provision made for springing the bolt 216 to the retracted position by contacting the strike plate 49. This type of bolt makes it necessary for the operator to have his key if he desires to lock the door or to leave it in the partially open secured position when leaving the room.

This door securing means can also be used to an advantage on a door equipped with the automatic closing means, since the bolt will engage against notch 62 in the bar to maintain the door in a fixed partially open position regardless of the action of the door closing device or any other force that might tend to urge the door either toward the open or closed position.

Referring now to Figs. 21, 22, and 23 wherein is shown a different arrangement of the securing bolt and latch member. It will be noted that the latch bolt 188 is positioned directly beneath the lock bolt 216 thus making it possible to materially lessen the length of wall members 38 and 40 and door plate 80. The lock bolt and associated parts are substantially identical with those shown in Fig. 17 and operate in like manner.

The latch bolt housing 186 is mounted in a morticed recess 184 which extends inwardly from the edge of the door and is securely attached to the plate 80 so that the latch bolt normally extends outwardly from the edge of the door as clearly shown in Figs. 21 and 22. This latch bolt is operable from either side of the door by operating the knobs 200 or 202 as described above. While the mechanism shown for operating the latch bolt would necessarily move at each movement of the knob; however, it is quite apparent that any of the ordinary latch bolts might be used including the one in which the latch bolt can be depressed by forcing out on the outer inclined surface 220 thereof without moving the knob.

The housing plates 38 and 40 are provided with registered openings 224 and 226 respectively. These openings are in alignment with the latch bolt 188 when the door is in the closed position, thus making it possible for the latch bolt to ride over the outer face of wall 40 and ordinarily drop into position for latching as clearly shown in Fig. 22. It will be noted that the slot 58 formed

in extension bar 50 is in alignment with the openings 224 and 226 so that the latch bolt 188 will extend therethrough when in the latched position and will engage both wall plates 38 and 40 as clearly shown.

A recess 228 is formed in the door jamb 28 to permit the latch bolt to extend slightly beyond the wall plate 38. Due to the fact that the inner edge of the latch bolt 188 is beveled at 220, that portion of the bolt which extends through bar 50 will be narrower than the main body of the bolt, thus making it possible to position the bolt through bar 50 without increasing slot 58 to an objectionable width.

To facilitate proper movement of latch bolt 188 and to prevent damage to the woodwork of the door casing, a striker lip 230 is provided, which is integral with the wall plate 38. When the latch bolt 188 is moved to the latching position, extension bar 50 will always be in the retracted position with the slot 58 in proper alignment to receive said bolt. As the door is being opened, the extension bar 50 will be moved outwardly more rapidly than the latch bolt so that when the latch bolt drops from the wall plate 40 it will not interfere with the extension bar. This is also true when the door is being moved to the closed position. This arrangement of the latch bolt has a material advantage in that it secures the extension bar 50 in the closed position under normal conditions when the door is latched.

While this modified form has been shown with the square lock bolt 216, it is also possible to use the beveled type of bolt such as shown at 72 in combination with this latch bolt.

The mounting of this door securing means to the door and door jamb is very simple and does not require any careful measurements since the parts are so constructed and related as to make it impossible to mount the parts in any other way than the proper relative relation. When it is desired to use only the secondary latching bar 188, the operator simply forces the bolt 72 to the retracted position, then turns knob 176 to force bolt 174 into the notch 182, thus making the bolt 72 inoperative.

What is claimed as new and is desired to be protected by Letters Patent is:

1. In a door securing device, a housing having an inner and an outer wall secured within a recess formed in the face of the door jamb, said outer housing wall having a bight formed therethrough, a slotted extension bar pivotally mounted within said housing on a pivot secured at its opposite ends to said inner wall and outer wall respectively for limited extension therefrom, a bolt mounted for longitudinal sliding motion in said door to extend into said bight to selectively secure said door in the closed position to engage said extension bar or to release the door for opening, a screw mounted in said inner housing wall to secure the housing to said jamb, the head of said screw being covered by said extension bar when the bar is in the extended operative position and means operable from both sides of said door to selectively position said bolt to any one of said three predetermined positions.

2. In a door securing device, a housing having an inner and an outer wall secured to the face of the door jamb, said housing having a bight formed into its outer wall, a slotted extension bar pivotally mounted on a pivot carried by said inner and outer walls within said housing behind said outer wall for limited extension therefrom, a

bolt of rectangular cross sectional area, having oppositely disposed horizontal slots formed on its top and bottom portions, carried by the door for sliding movement relative thereto and adapted to enter said bight and engage said bar and move it toward and from the extended position as the door is moved from and toward the closed position, and means securing said inner housing wall to said jamb covered by said extension bar when said bar is in the extended position.

3. In a door securing device, an extension bar pivotally mounted within a housing having an inner and an outer wall to receive the opposite end portions of the pivot pin of said bar and being secured flush with the face of the door jamb and with its outer wall covering said bar, a bolt slidably mounted in the door for engagement with said extension bar, means freely operable from one side of the door only for sliding said bolt to and from the bar engaging position, a key oper-

ated means on the opposite side of said door engaging said first named bolt operating means and operable to adjust said bolt to its various positions, and resilient means operable to frictionally engage said bolt when it is in the bar securing position whereby its position is indicated to the operator.

4. In a door securing device, a housing secured to the face of the door jamb, a slotted extension bar pivotally mounted in said housing for limited extension therefrom, a bolt slidably carried by the door to operatively engage said extension bar to move it to and from the extended position as the door is operated on its hinges, and a latch bolt carried by said door adapted to secure said extension bar against accidental movement in the retracted position when the door is closed.

20
